AUSTRALIA, AUSTRALIA.

CARBURETER.

1,025,816.

Specification of Letters Patent.

Patented May 7, 1912.

Application filed April 10, 1911. Serial No. 620,152.

To all whom it may concern:

Be it known that we, JACOB MATTHIAS LOFTHOUSE and EMILY ROSALIE BOOTY, subjects of the King of Great Britain, residing at Perth, Western Australia, and Commonwealth of Australia, have invented certain new and useful Improvements in Carbureters, of which the following is a specification.

Our invention relates to a valve device for 10 making carbureted air by charging atmospheric air with petrol or other volatile hydrocarbons and the said device consists of a carbureter through which air is forced under pressure and from which the mixture 15 produced is taken directly into the service pipes and without the medium of a gas storage tank, the object of our invention being an improved valve device whereby the predetermined proportion of petrol is automatically 20 governed by the take off of the mixture and whereby the air and petrol or other volatile hydrocarbon is mixed in predetermined and approved proportions and irrespective of the amount of the take off of the 25 mixture.

The construction and use of our device will now be explained with the aid of the attached drawing in which—

Figure 1 shows a vertical section while 30 Fig. 2 is a detail elevation of the slotted bell. In said drawing α is the valve casing or chamber having the concentric well α^1 for holding the mercury or other sealing agent and into which dips the inverted and floating bell b having the peripheral mixture exit slots b^1 of any number and as clearly seen in Fig. 2. This bell has the guide rod b^2 working in the bracket b^3 secured to the casing α as shown. To this casing α at its 40 top is connected the mixture take away pipe b^4 . This floating bell carries a down tube c and which is operatively connected thereto by the lazy tongs movement c^1 working on its fixed pivot c^2 . In this tube is formed the 45 petrol inlet port c^3 and said tube dips into a body of mercury d contained at the bottom of the central chamber d^1 and said chamber is made integral with the valve case α . The 50 tube c telescopes down and around another and inner tube e which is rigidly held in the chamber d^1 . This tube terminates in a drip point as e^1 from whence the petrol falls into

the carbureting chamber e^2 shown broken away in the drawing.

The valve chamber α carries a bracket f 55 having a split or spring eye f^1 and in which by the screw f^2 is adjustably held the petrol float chamber g . By means of this adjustment bracket the vertical position of the petrol float chamber is regulated so as to 60 govern the height of the petrol g^1 in its chamber d^1 of the casing α , and to said chamber d^1 the petrol is fed by the pipes g^2 from the float chamber g which latter chamber is supplied by the pipe g^3 from the 65 petrol tank not shown. The casing is provided with the pipes as j and j^1 whose function is respectively to maintain an equilibrium of pressure within the valve chamber, the float chamber g and the petrol tank. 70 The valve chamber is further provided with the pipes k and k^1 through which the mercury as d and d^1 is introduced into their own chambers and these pipes further act as 75 scour out passages and are furnished with suitable pet cocks.

The action of the appliance is automatic and is as follows. In the drawing the bell b is shown in its lower position and the petrol inlet port c^3 exposed and which positions 80 are maintained as long as there is no take off of mixture through pipe b^4 . As soon as such take off occurs the pressure beneath the bell b operates and causes the bell to rise and thereby exposing the needful area of the 85 exit slots b^1 thus permitting the mixture to pass through and into the upper portion of the chamber α and out by the pipe b^4 .

The rise of the bell by means of the lazy tongs movement c^1 depresses the tube c so 90 causing the petrol inlet port c^3 to become immersed in the petrol g^1 and thus allowing said petrol to flow into the tube c and from thence down into the petrol discharge tube e from whence it issues at the drip point e^1 95 into the carbureting chamber e^2 . In this latter chamber the petrol meets the incoming air and whereby a gaseous mixture of a fixed quality is generated. This newly made gaseous mixture proceeds upward through 100 the chamber α and so through the now exposed exit slots b^1 of the now raised bell b end so to the service pipe b^4 . The quality of the mixture is governed by the propor-

tionate areas of the exit slots and the petrol inlet port c^3 .

It is apparent that the greater the consumption of the mixture the higher the bell 5 will rise and consequently the deeper the immersion of the petrol inlet port c^3 within the petrol g^1 and thereby increasing the feed of the petrol to the carbureting chamber and all in proportion with the take off 10 of the gaseous mixture through pipe b^4 . By the rise or fall of the floating bell consequent on the demand for gaseous mixture it is obvious that the exit slots b^1 and petrol inlet port c^3 will respectively become exposed or immersed to the proportionate extent so governing the discharge of petrol at 15 e^1 to the carbureting chamber e^2 . The mercury d seals the petrol g^1 and prevents it from ascending at the lower end of the tube 20 e . As soon as the consumption of mixture ceases the bell falls to zero as in the drawing so raising the bell and exposing the petrol port c^3 and so shutting off the feed of the petrol from pipe $e-e^1$.

25 What we claim as our invention and desire to secure by Letters Patent is—

1. A carbureter comprising in combination a casing having a carbureting chamber adapted to receive a supply of air, a chamber 30 to contain a body of the liquid to be volatilized and also having an exit for the mixture, said casing also having an annular chamber containing a sealing liquid, a bell operative in said annular chamber of the 35 casing and subject to fluctuations of pressure of the mixture at said exit, said bell also having exit ports therein controlled by said sealing liquid and adapted for the passage therethrough of the mixture from the 40 carbureting chamber, a valve for controlling the supply of liquid to be volatilized to said carbureting chamber, and an operative connection between said bell and valve for controlling the operation of the latter 45 by the movements of the former.

2. A carbureter comprising in combination a casing provided with an exit and having a carbureting chamber adapted to receive a supply of air and also chambers containing bodies of sealing liquid, one of said 50 chambers also containing a body of the liquid to be volatilized, a bell floating in the sealing liquid in one of said chambers and subject to the pressure of the mixture at 55 said exit, a tube operative in the sealing liquid and also the liquid to be volatilized in the other chamber and embodying means for controlling the supply of liquid to be volatilized in said carbureting chamber, and 60 an operative connection between said bell and tube for depressing the latter to establish a supply of liquid to be volatilized when said bell rises.

3. A carbureter comprising in combination a casing provided with an exit and also

having chambers therein containing bodies of sealing liquid, one of said chambers also containing a body of the liquid to be volatilized, a carbureting chamber in said casing adapted to receive a supply of air, a bell floating in the sealing liquid in one of said chambers and subject to the pressure of the mixture at said exit, said bell also having exit ports therein for the passage therethrough of the mixture from the carbureting chamber, a tube operative in the sealing liquid and also the liquid to be volatilized in the other chamber and embodying means for controlling the supply thereto of liquid to be volatilized in said carbureting 70 chamber, and an operative connection between said bell and tube for causing predetermined relative movements thereof in reverse directions.

4. A carbureter comprising in combination a casing provided with an exit for the mixture and also having chambers therein containing bodies of sealing liquid, one of said chambers also containing a body of the liquid to be volatilized, a carbureting chamber in said casing adapted to receive a supply of air, a bell operative in one of said chambers and subject to the pressure of the mixture at said exit, said bell also having exit ports for the passage of the mixture 85 from the carbureting chamber, a tube operative in the other chamber and embodying means for controlling the supply of the liquid to be volatilized in said carbureting chamber, and a lazy tong connection between said bell and tube for causing predetermined relative movements of said elements in reverse directions.

5. A carbureter comprising in combination a casing provided with an exit for the mixture and also having chambers therein containing bodies of sealing liquid, one of said chambers also containing a body of the liquid to be volatilized, said casing having a carbureting space adapted to receive a supply of air, a bell operative in one of said chambers and subject to the pressure of the mixture at said exit, a tube operative in the other chamber and embodying means for controlling the supply of the liquid to be volatilized to said carbureting space, and a pipe leading into said tube for conducting therefrom the liquid to be volatilized 105

6. A carbureter comprising in combination a casing having a carbureting chamber adapted to receive a supply of air, said casing being also provided with an exit for the mixture and a chamber to contain a body of the liquid to be volatilized, a liquid-containing annular chamber being also formed in the casing, a bell operative in the liquid of said annular chamber and having exit ports for the passage of the mixture therethrough, said bell being subject to the pressure of the mixture at said exit, and the exit 115 120 125 130

ports in the bell being controlled by the liquid in which the bell operates, a valve for controlling the flow of liquid to be volatilized to said carbureting chamber, and means 5 for maintaining said liquid in the carbureter casing at a predetermined level.

In testimony whereof we have hereunto

set our hands in presence of two subscribing witnesses.
